UNITED STATES PATENT OFFICE.

SIMEON S. JACKSON, OF BOSTON, MASSACHUSETTS, ASSIGNOR TO THE STAFFORD COMPANY, OF READVILLE, MASSACHUSETTS, A CORPORATION OF NEW JERSEY.

LOOM SHUTTLE-RELOADER.

1,130,605.

Specification of Letters Patent.

Patented Mar. 2, 1915.

Application filed August 1, 1913. Serial No. 782,461.

To all whom it may concern:

Be it known that I, SIMEON S. JACKSON, a subject of Great Britain, residing at Readville, Boston, in the county of Suffolk, State 5 of Massachusetts, have invented a certain new and useful Improvement in Loom Shuttle-Reloaders, of which the following is a specification, reference being had therein to the accompanying drawings.

10 The invention provides a manually-controlled loom-shuttle reloader by means of which a weaver or a helper can introduce readily, at convenience, a fresh bobbin or other weft-carrier into a spent shuttle that 15 has been removed from its place on the lay of a loom.

One general object of the invention is to render it practicable to use in ordinary looms, and in shuttle-changing automatic 20 weft-replenishing looms, shuttles constructed without the usual hinged spindle and having instead thereof one or more holding clips or retainers engaging with a bobbin or other weft-carrier to hold it in place 25 in a shuttle. In this connection one of my special aims is to facilitate the employment in shuttle-changing weft-replenishing looms and ordinary looms of shuttles of the said 30 class of the type at present used only in bobbin-changing replenishing looms. These are constructed to permit a bobbin or other weft-carrier to be inserted into the same by being pushed bodily in at one side of the 35 shuttle, and to be ejected by being pushed bodily out through the other side thereof. Such shuttles have an opening through the same from top to bottom, the insertion being effected at the top and the ejection at the bottom. They usually are furnished 40 with one or more clips or retainers therein to hold the bobbin or other weft-carrier in place within the shuttle. The usual clip or retainer performs the said function by engaging with the head or base of the bobbin 45 or other weft-carrier, the said head or base being pushed bodily into the grasp of the clip or retainer as the bobbin or weft-carrier is inserted into the shuttle, and being pushed bodily out of such grasp as the bobbin or 50 weft-carrier is ejected. The clip or retainer is constructed to take a powerful and firm hold upon the head or base of the weft-carrier, in order to prevent the weft-carrier from being dislodged during the working of 55 the loom, and in order to prevent the free

end of the weft-carrier and its yarn-load from swinging either upward or downward. Owing to the inconvenience and difficulty of inserting or changing bobbins or other weft-carriers by hand in the case of shuttles of this class, such shuttles are not employed at the present time in ordinary looms, and have been employed only to a limited extent in shuttle-changing weft-replenishing looms. Instead, shuttles having hinged spindles 60 are employed, because of the greater facility in inserting and changing bobbins, etc., by hand therein. At the present time I know of no devices for use by a weaver or helper for manually effecting the insertion or 65 change of bobbins or other weft-carriers in the case of a spent shuttle of the class in question that has been removed from a loom.

Another general object of the invention is to facilitate the reloading of shuttles so as 70 to give a weaver more time to attend to other duties, and also so as to obtain the very important result of considerably increasing the number of plain looms, or shuttle-changing weft-replenishing looms, 75 that can be tended by a weaver, and also, in the case of shuttle-changing weft-replenishing looms, the number of looms that a bobbin-boy can take care of by keeping the shuttles loaded with weft and threaded and 80 in place in the magazines of the looms.

The invention consists in a manually-controlled reloader for loom-shuttles having a through-passage for insertion and discharge of filling-carriers and a clip which 85 holds a filling-carrier within the shuttle by grasping the head of the filling-carrier, for enabling an operative to effect the re-loading of a shuttle which has been removed from a loom in which it is employed, the 90 said reloader comprising a shuttle-rest for a shuttle free from the loom, a weft-carrier inserter distinct and separate from the regular weft-replenishing instrumentalities of a loom, and means for operating the parts 95 at the will of the operative to insert a fresh weft-carrier into the clip or other grasping means of a shuttle applied manually to the said shuttle-rest.

The invention, in several forms of embodiment, is illustrated by the accompanying drawings, in which latter—

Figure 1 shows in front elevation certain portions of the magazine-ends of two adjacent shuttle-changing weft-replenishing 110

looms, and a shuttle reloader of one form between them. Fig. 2 is a plan view of certain of the parts shown in Fig. 1. Fig. 3 is a partly sectional side elevation of the upper portion of the shuttle reloader of Figs. 1 and 2. Fig. 4 is a front elevation of another form of shuttle reloader. Fig. 5 is a plan view thereof. Fig. 6 is a side elevation thereof partly in vertical section on line 6, 6, 10 of Fig. 4.

Having reference to the drawings, the two looms which are shown partly in Fig. 1 may be, for instance, of the character of the automatic shuttle-changing weft-replenishing loom shown and described in U. S. Letters Patent No. 945,722, granted January 4, 1910. The said looms are respectively, right hand and left hand, and their magazine-ends are next to each other. The two loom-frames 20 are marked 1, 1. The hoppers or magazines 2, 2, contain the loaded fresh or reserve shuttles 3, 3, 3, etc. The said shuttles are of the type hereinbefore mentioned as peculiar to bobbin-changing weft-replenishing looms, 25 namely having a weft-chamber which is open at both the top and the bottom of the shuttle so that an opening or through passage extends entirely through the shuttle from its top surface to its bottom surface. Each 30 thereof is provided with a U-shaped spring clip or retainer 3^a, Fig. 2, designed for engagement with the head or base of a weft-carrier x , and permitting such weft-carrier to be inserted into place within the shuttle by being forced down from above into the 35 weft-chamber, so that its head or base shall enter between the engaging members of the said clip or retainer, and also permitting the said weft-carrier to be expelled from the 40 shuttle by being forced downward from the weft-chamber through the bottom of the shuttle, thereby withdrawing its head or base from between the said engaging members. The pegs or pins 4, 4, on the said hoppers 45 or magazines have wrapped around the same the leading weft-ends which are drawn out through the eyes of the said shuttles, in usual manner. In the working of the said looms, weft-replenishment is effected by the 50 automatic discharge from the lay of a loom of the shuttle previously at work thereon, and the automatic transfer of a fresh or reserve shuttle from the hopper or magazine to the lay to take the place of the shuttle 55 which has been thus discharged.

At 5, 5, are the catcher-boxes in which the spent shuttles are received when they are discharged from the respective looms.

Referring now to the shuttle-reloader, 60 and first to Figs. 1, 2 and 3, the shuttle-rest thereof consists of a bed or shelf 6, which in this instance is mounted upon a post or standard 7 stationed between the magazine-ends of the two neighboring looms. The advantage of this position of the shuttle-re-

loader is that a weaver or helper standing at the shuttle-reloader is within reaching distance of the catcher-boxes 5, 5, and magazines 2, 2, of both looms. Without moving from his place, he can take a shuttle from either catcher-box, reload it by means of the shuttle-reloader, and place it in the magazine of the loom in which it is employed. In other words, the shuttle-reloader serves for both looms, enabling the expelled shuttles of both looms to be reloaded and replaced in the respective magazines practically without change of position on the part of the operative who performs the work of reloading. For the proper positioning of a shuttle which is to have a weft-carrier placed therein, the shuttle-rest is furnished with end-gages 8, 8. These end-gages in the present instance are shaped to receive and fit the opposite ends and tips of a shuttle 85 contacting with the top surface of the bed or shelf 6, and they serve to determine the position of the shuttle lengthwise with relation to the pusher 9 and the discharge-opening 6^a, Fig. 3, through the shuttle-rest. The 90 said discharge-opening is indicated in dotted lines in Fig. 1. The end-gages are secured in place by means of extensions thereof which are engaged by bolts 10, 10, the said bolts serving to attach the end-gages to the 95 bed or shelf. To provide for adjustment of the end-gages to suit the length of the shuttles, and to cause the shuttles to assume the proper position relative to pusher 9 and discharge-opening 6^a, the said extensions are 100 slotted longitudinally at 11, 11. The bed or shelf is furnished with side-guides for a shuttle applied to the shuttle-rest. Such side-guides in the present instance are constituted by raised lips 12, 12, at front and 105 rear of the opening 6^a. When a shuttle is properly applied to the shuttle-rest, the end-gages and side-guides position it so that the vertical opening through the shuttle registers with the opening 6^a of the shuttle-rest. 110 The pusher 9 may be of any approved construction adapting it for the purpose herein indicated. It may be variously applied and supported. Herein, it is in the form of an arm that is mounted to swing 115 about a pivotal support 9^a, such support being provided in connection with a bracket 13 projecting rearward from the casting of which the bed or shelf forms part. The pusher is raised, and kept normally in a 120 raised position by means of a spring 14, as in Figs. 1 and 3, the limit of its rising movement being determined by means of a stop-projection 9^c with which it is furnished, 125 Figs. 2 and 3, which strikes against the bracket 13. The acting portion of the pusher is constructed and arranged to enable it to act against a fresh weft-carrier x' , Fig. 3, located immediately above the weft-chamber 130 of a shuttle that has been applied to the

shuttle-rest, and push it into the said weft-chamber, thereby placing it within the grasp of the clip or retainer 3^a. In Fig. 3 the fresh weft-carrier α' is shown resting 5 upon the weft-carrier α already occupying the weft-chamber of the shuttle. As the fresh weft-carrier enters the weft-chamber it expels the weft-carrier α from the shuttle downward through the opening 6^a. The 10 extent of the working stroke of the pusher 9 is regulated by means of an adjustment-screw 15 applied thereto which terminates the said stroke, by striking upon the stop-projection 16 in connection with the shelf 15 or bed, when the fresh weft-carrier has been 15 fully introduced into the grasp of the clip or retainer. This stop-device prevents the fresh weft-carrier from being driven too far. For the convenient actuation of the 20 pusher by hand, it is shown furnished with a handle 9^b. For the convenient actuation of the pusher by foot, a treadle 17 is provided, in operative connection with the pusher. The said treadle is held normally 25 in a raised position by means of a spring 18, and it is shown as combined operatively with the pusher by means of a rod-connection 19, 20. The lower rod-section 19 is connected pivotally at its lower end to the 30 treadle, and the upper rod-section 20 is connected pivotally to the pusher. The two rod-sections are connected operatively with each other by forming said upper rod-section with an eye 20^a, Fig. 1, through which 35 the upper portion of lower rod-section 19 extends. The said upper portion has a head 19^a above the said eye. Normally, the spring 18 holds elevated the treadle and the rod-section with its head 19^a, so that spring 14 40 is free to operate to cause pusher 9 to occupy its normal elevated position. When the treadle is pressed down, the downward movement of rod-section 19 causes its head 19^a to act upon eye 20^a to draw down rod-section 20, thereby actuating the pusher. 45 When the pressure upon the treadle is relieved, the treadle and pusher are raised to their normal positions again by their respective springs. The described construction 50 enables the pusher to be operated manually by either hand or foot, and the loose connection between the pusher and treadle enables the pusher to be operated by hand without incidentally communicating 55 movement to the treadle. By arranging so that the inserted may be operated by foot, both hands of the attendant are left free to be used in handling and placing the shuttle and fresh weft-carrier, and in finding and drawing off the leading end of the 60 yarn therefrom. One hand may be used to hold the weft-carrier in position to be acted upon by the inserter, while the other holds the end of the yarn extended and may be 65 employed in threading the shuttle in the

case of hand-threading or so-called slit-threading shuttles.

Figs. 4, 5 and 6 illustrate a shuttle-reloader in which the loading operation is effected by a bodily movement of the shuttle 70 relative to a weft-carrier inserter, the latter not being required to move for the performance of the said operation.

In Figs. 4, 5 and 6 the shuttle-rest 6^c is mounted by means of downward extensions 75 or legs 6^a, 6^d, thereupon a pivotal pin 22, carried by the casting 23 attached to the upper end of the standard or post 7^a. It is shown in said figures in its normal position, in which it may rest against a backstop 24. 80 As applied to the shuttle-rest, the shuttle 3 lies on one lateral side upon the shelf of the shuttle-rest, with its opening directed from front to rear. At the rear of the shelf upon which the shuttle is placed, the shuttle-rest 85 is provided with an upright back 6^d having an opening 6^e therethrough for the escape of a weft-carrier expelled from the shuttle. Below the said opening the shuttle-rest is furnished with an inclined plate 6^f to deflect rearwardly the expelled weft-carrier as it falls from the opening 6^e. Lateral wing-portions of the shuttle-rest are furnished 90 with forwardly-projecting end-gages 8^c, 8^e, for engagement with the shuttle-tips, to 95 locate the shuttle endwise. These end-gages are provided with inwardly-projecting portions 8^d, 8^d, to engage with the shuttle-tips in front so as to prevent displacement of the shuttle forward. A handle 8^e serves for 100 enabling the shuttle-rest to be swung relative to the weft-carrier inserter. The weft-carrier inserter 9^b is in this instance a fixture upon the casting 23. It is formed with rests 105 9^f and 9^g for the head or base and tip of the fresh weft-carrier α' which is to be introduced into the shuttle, and between such rests it is formed to support the said weft-carrier against forward thrust as the shuttle-rest and shuttle are swung toward the weft-carrier inserter. An end-gage 9^m upon the inserter alongside the rest for the base or head of the weft-carrier α' insure the proper 110 position of the said weft-carrier lengthwise with respect to the shuttle-chamber, so that the weft-carrier shall properly enter such chamber and its head or base shall become engaged properly with the clip or retainer of the shuttle. 115

The employment of shuttles of the class herein referred to, and of a shuttle reloader such as described greatly facilitates and expedites the work of reloading spent shuttles, so that this part of the work may be performed more readily and quickly than heretofore. This enables the weaver to look after more looms even when he performs the duty of reloading the spent shuttles himself, and when a bobbin-boy is employed to distribute weft or filling to the different looms 120 125 130

he is enabled to perform the reloading also, and it is rendered practicable for both the weaver and the bobbin-boy to take care of a larger number of looms than would be possible without the employment of shuttle reloaders.

I claim as my invention:—

1. A manually-controlled reloader for loom-shuttles having a through-passage for insertion and discharge of filling-carriers and a clip which holds a filling-carrier in place within the shuttle by grasping the head of such filling-carrier, for enabling an operative to effect the reloading of a shuttle which has been removed from a loom in which such shuttle is employed, the said reloader comprising a shuttle-rest for a shuttle free from the said loom, a weft-carrier inserter distinct from the elements of the regular automatic weft-replenishing mechanism of a loom and acting in the direction of the said through-passage, and means for operating the parts at the will of the operative to insert a fresh weft-carrier bodily transversely into the clip or other grasping means of the said shuttle and expel the weft-carrier previously contained in the shuttle.

2. Means for reloading shuttles which have been removed from the loom or looms in which they are employed, said shuttles having each a through-passage for insertion and discharge of filling-carriers and a clip which holds a filling-carrier in place within the shuttle by clasping the head of the filling-carrier, comprising a shuttle-rest for a shuttle free from its loom, and a manually-operated weft-carrier inserter distinct from the elements of the regular automatic weft-replenishing instrumentalities of a loom, and acting in the direction of the said through-passage, for inserting a fresh weft-carrier into the clip or other grasping means of the said shuttle and expelling the weft-carrier previously contained in the shuttle.

3. A manually-controlled reloader for loom-shuttles having a through-passage for insertion and discharge of filling-carriers and a clip which holds a filling-carrier in place within the shuttle by grasping the head of such filling-carrier, for enabling an operative to effect the reloading of a shuttle which has been removed from a loom in which such shuttle is employed, the said reloader comprising a shuttle-rest for a shuttle free from the said loom, a weft-carrier inserter distinct from the elements of the regular automatic weft-replenishing mechanism of a loom and acting in the direction

of the said through-passage, means for positioning the shuttle lengthwise with relation to the weft-carrier-inserter, and means for operating the parts at the will of the operative to insert a fresh weft-carrier bodily transversely into the clip or other grasping means of the said shuttle.

4. A manually-controlled reloader for loom-shuttles having a through-passage for insertion and discharge of filling-carriers and a clip which holds a filling-carrier in place within the shuttle by grasping the head of such filling-carrier, for enabling an operative to effect the reloading of a shuttle which has been removed from a loom in which such shuttle is employed, the said reloader comprising a shuttle-rest for a shuttle free from the said loom, a weft-carrier inserter distinct from the elements of the regular automatic weft-replenishing mechanism of a loom and acting in the direction of the said through-passage, end-gaging means for positioning the shuttle lengthwise with relation to the weft-carrier-inserter, means for adjusting said end-gaging means to suit the length of the shuttle, and means for operating the parts at the will of the operative to insert a fresh weft-carrier bodily transversely into the clip or other grasping means of the said shuttle.

5. A manually-controlled reloader for loom-shuttles having a through-passage for insertion and discharge of filling-carriers and a clip which holds a filling-carrier in place within the shuttle by grasping the head of the filling-carrier, for enabling an operative to effect the reloading of a shuttle which has been removed from a loom in which such shuttle is employed, the said reloader comprising a shuttle-rest for a shuttle free from the said loom, a weft-carrier-inserter distinct from the elements of the regular automatic weft-replenishing mechanism of a loom and acting in the direction of the said through-passage, means for positioning the shuttle lengthwise with relation to the weft-carrier-inserter, means for operating the parts at the will of the operative to insert a fresh weft-carrier bodily transversely into the clip or other grasping means of the said shuttle, and means to limit the inserting stroke.

In testimony whereof I affix my signature in presence of two witnesses.

SIMEON S. JACKSON.
